UNITED STATES PATENT OFFICE

2,481,173

RING GRINDING FIXTURE

Robert Stenwall, Newaygo, Mich., assignor to
 Muskegon Piston Ring Company, Muskegon,
 Mich., a corporation of Michigan

Application October 20, 1947, Serial No. 780,971

6 Claims. (Cl. 51—236)

1

This invention relates to a simple, novel, but very practical and effective attachment for ring grinding machines of the type shown in my Patent #2,397,298 granted March 26, 1946.

In the structure of the aforesaid patent the grinding of rings, and particularly piston rings at their outer curved surfaces, is very efficiently attained. Machines designed and built for piston ring grinding are capable of handling piston rings in substantially all of the diameter sizes, such as are used in internal combustion engines of automobiles. There are other rings, some of which may be packing rings, and others continuous rings without any partings therein, of smaller diameters than the smallest diameter of automotive piston rings, which can not be effectively ground upon the machines which have been built for piston ring grinding in accordance with the structure of my patent. Of course, other machines designed for smaller diameter rings less than what in general is about the smallest piston ring diameter, namely, 2½ inches, could be built for such small ring grinding exclusively. This would necessitate the expense of a complete machine and the cost of its occupying floor space in a factory, not only at times when it was in use, but at all other times.

The present invention is directed to a simple, easily connected and quite as readily disconnected attachment for the piston ring grinding machines which have been built, and with such attachment, the other rings of the smaller diameters wanted may be quite as accurately and effectively ground when such attachment is used, as the larger diameter piston rings are ground in the existing machines without the attachment. Many rings having a diameter of approximately one inch and varying in diameters between one inch and the minimum size of internal combustion engine piston rings, and usable for many purposes, are rapidly ground with high quantity production with my invention.

It is an object and purpose of the present invention to provide a novel, practical and easily connected attachment for piston ring grinding machines of the structure disclosed in the aforesaid patent, with which the numerous sizes and diameters of rings of the lesser diameters wanted, may be effectively ground with rapid, high quantity production.

An understanding of the invention may be had from the following description, taken in connection with the accompanying drawings, in which,

Fig. 1 is a transverse vertical section through one of the piston ring grinding machines made

2

in accordance with Patent #2,397,298, and to which the novel attachment of the present invention is connected, said attachment being shown in elevation and transverse section,

5 Fig. 2 is a side elevation and partial vertical section of the structure shown in Fig. 1,

Fig. 3 is a plan view, and

Fig. 4 is a fragmentary elevation of the shim attachment used when rings of smaller diameter 10 are to be ground.

Like reference characters refer to like parts in the different figures of the drawings.

On a base plate 1, spaced apart supporting posts 2 and 3 are secured, which are to carry the arbor on which a plurality of rings to be ground is mounted. At opposite sides of the posts, and mounted upon the base in any suitable manner, are lower horizontal shafts 4 from which spaced arms 5 extend upwardly between the upper ends of which rubber covered horizontal rollers 6 are mounted. Bars 7 connect the arms 5 at each side of the structure described and are connected by links 8 with rocking arms 9 for moving the rollers 6 inwardly and outwardly 20 toward the arbor 10, upon which a plurality of rings to be ground are held. Said arbors 10 at each end have bearings 11 which are to be received in blocks 12 secured at the upper ends of the posts 2 and 3. The blocks 12 are provided 25 with concave recesses at their upper sides in which spaced hardened pins 13, as shown in Fig. 4, are located. The rings 14, which are to be ground, are of larger interior diameter than the diameter of the arbor 10 over which they are 30 located and from which they are suspended.

The structure thus far described is illustrative of the environment of my invention and is substantially identical with that disclosed in my earlier patent. With the rings 14 sufficiently 35 large in diameter, and usually at least 2½ inches in diameter or more, the rollers 6 may be swung inwardly toward each other to bear on opposite sides of the rings above the center of the arbor. The rollers are driven so that the rings are 40 turned about their centers in the operation of the machine. Such driving mechanism forms no part of the present invention and is not shown or described, but it is fully shown and described in my earlier patent which has been mentioned.

50 In the present invention a bar 15 is detachably connected at the inner side of each of the posts 2 and 3 by bolts or screws. Horizontal shafts 16 extend between the end portions of the bars 15.

55 Arms 17 are securely connected to said shafts 16 at the ends thereof and extend upwardly. Rollers 18 are mounted on and extend between

the upper ends of the arms 17, one roller 18 at each side of the arbor 10. The rollers 18 have axes of rotation above the rotative axes of the rollers 6 and are between said rollers 6 and the rings 14 which are to be ground.

From each of the shafts 16 an arm 19 extends downwardly. The lower ends of the two arms 19 are connected by a coiled tension spring 20 as shown, the effect of which is to tend to move the rollers 18 outwardly and thus maintain them against the driving rollers 6.

The grinding wheel 21, having a horizontal under-grinding face, is disposed the same as in my issued patent, with its lower face in a plane such that the turning rings 14 are brought to said grinding face and the plurality of rings on the arbor, as shown in Fig. 3, simultaneously ground. The plates 22 at the inner sides of the posts 2 and 3 are hardened wearing plates against which the end rings 14 on the arbor may contact. Because the arbor 10 for the small diameter rings is of a smaller diameter than the arbor used with the larger piston rings, the arbor bearing blocks 12 are elevated by the interposition of a spacer or shim 23 (Fig. 4) between the upper ends of the posts 2 and 3 and the lower sides of the blocks.

It is evident that the connection of the attachment to the machine to condition the machine to grind the rings of small diameter is very quickly made. Bolts are passed through the bars 15 into the posts 2 and 3, and the blocks 12 are removed, the spacers or shims 23 located in place, and then the blocks 12 reconnected.

The rings are driven by the rollers 6 through the interposed idle rollers 18 at the times when said rollers 6 are moved inwardly toward each other, and when rollers 6 are moved outwardly in the operation of the machine, the rollers 18 follow them by reason of the action of the spring 20, whereupon the rings on an arbor which have been ground may be removed with the arbor, and another arbor with unprocessed rings to be ground put in place of those removed, the machine operating the same as described in my Patent #2,397,298.

The attachment described has proved very practical and useful. It makes unnecessary the building of a separate complete machine for grinding the rings of smaller diameters and utilizes machines designed and built for grinding rings of a larger diameter. Not only is the expense of building separate machines avoided, but the floor space in a factory is not increased. The demand for the small diameter rings is increasing. Their rapid grinding at their outer curved surfaces to precise dimensions and in large quantity economical production, is thus most effectively and economically attained.

The invention is defined in the appended claims and is to be considered comprehensive of all forms of structure coming within their scope.

I claim:

1. An attachment for ring grinding machines comprising, two spaced apart horizontal bars located in substantially the same plane adapted to be connected to vertical spaced arbor supporting posts, a horizontal rock shaft mounted on and extending between the ends of said bars, one of said rock shafts extending between one of the ends of the spaced bars and the other between the other ends thereof, arms secured to said rock shafts adjacent their ends extending upwardly therefrom, horizontal rollers rotatably mounted at the upper ends of said arms, a resilient cover on each of said rollers, and yielding means con-

nected with said arms normally tending to move said rollers away from each other.

2. A structure as defined in claim 1, said yielding means comprising members connected one to each rock shaft and extending downwardly therefrom, and coiled spring means connecting the lower ends of said members tending to pull said members toward each other and move the rollers away from each other.

3. In a machine as described, an arbor support including, spaced apart posts having recessed upper ends adapted to support the end portions of an arbor from which rings may be suspended, and an attachment mounted on said posts at the inner sides thereof comprising, a horizontal bar detachably connected to each post below its upper end, each bar having ends extending beyond the sides of the posts, rock shafts mounted on the end portions of said bars and extending between them, arms extending upwardly from the rock shafts, horizontal rollers mounted on and extending between the upper ends of the arms adapted to bear against opposed sides of rings on an arbor, each of said vertical posts having

15 a block at its upper end with a concave recess therein, means for detachably connecting said blocks to the posts, and a filler or shim between the lower end of each of said blocks and the upper end of each post detachably and removably connected with its associated block and post.

4. The elements of claim 3 in which said second rollers are movable toward and away from said arbor and yieldable means for moving them away from the arbor.

5. In a machine as described, an arbor support including, spaced apart posts having recessed upper ends adapted to support the end portions of an arbor from which rings may be suspended, and an attachment mounted on said posts at the inner sides thereof comprising, a horizontal bar detachably connected to each post below its upper end, each bar having ends extending beyond the sides of the posts, rock shafts mounted on the end portions of said bars and extending between them, arms extending upwardly from the rock

45 shafts, horizontal rollers mounted on and extending between the upper ends of the arms adapted to bear against opposed sides of rings on an arbor, and a member connected to each rock shaft extending downwardly therefrom, and a coiled tension spring connecting the lower ends of said members.

6. A machine of the class described comprising two spaced apart bearings, an arbor rotatably supported in said bearings and supporting a plurality of rings, a pair of rollers on opposite sides and parallel with said arbor and movable toward and from the arbor, means for rotating said rollers and a second pair of rollers smaller in diameter than the first rollers, extending parallel with the arbor and interposed between and in engagement with said first rollers and said rings above the horizontal centers thereof.
